CLAIM

The ornamental design for round tape measure, as shown and described.

DESCRIPTION

FIG. 1 is a top plan view of a round tape measure with its tape in its retracted orientation showing my new design;

FIG. 2 is a bottom plan view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top front right isometric view thereof;

FIG. 8 is a bottom left rear isometric view thereof; and,

FIG. 9 is a top plan view of a round tape measure of FIG. 1, except with its tape in a partially extended orientation; and,

FIG. 10 is a bottom plan view thereof.
